UNITED STATES PATENT OFFICE.

HUGHBERT W. McCABBE AND HOMER F. NORTON, OF SEATTLE, WASHINGTON.

BROODER.

1,207,424.

Specification of Letters Patent.

Patented Dec. 5, 1916.

Application filed July 3, 1915. Serial No. 37,884.

To all whom it may concern:

Be it known that we, HUGHBERT W. McCABBE and HOMER F. NORTON, citizens of the United States of America, and residents 5 of the city of Seattle, county of King, and State of Washington, have invented certain new and useful Improvements in Brooders, of which the following is a specification.

Our invention relates to brooders and 10 comprises certain features of construction which will be hereinafter described and particularly pointed out in the claim.

The chief object of our invention is to produce a brooder of simple construction, 15 capable of being easily kept in sanitary condition, one which will prevent tendency of the chicks to crowd and pile up and which will insure a constant and ample supply of fresh warm air while at the same time providing means whereby overheating and undercooling is prevented.

In the accompanying drawings are shown the preferred form of construction.

Figure 1 is a top view. Fig. 2 is a longitudinal vertical section. Fig. 3 is the same as Fig. 2 except that a different plan for adjusting the exit opening is shown.

It has been our object in this brooder to so construct the hover chamber that it 30 constitutes an inverted cup or pocket having an exit opening for the air, only at its lowermost part, whereby it will retain, trapped therein, a mass of warmed air, preventing its escape except as it is displaced 35 by the introduction of other air.

It has been our object further, to provide a means for supplying heated air to this hover chamber which substantially eliminates direct radiation of heat in the hover 40 chamber, the heat being supplied solely through convection.

The result of the means employed is the formation and maintenance of a blanket of hot air extending from the top of the hover 45 chamber down to the level of the upper edge of the exit opening, this maintaining a temperature which is the same at the same level all over the area of the chamber, but in which there is a lower cooler layer of a 50 depth determined by the level of the upper edge of the exit opening.

The hover chamber 1 may be of any suitable shape and construction and is, in principle, an unobstructed chamber. For con-

venience of access to the interior of this 55 chamber, I have made a section 2, of its top removable, this being held in place by cleats 20 which extend under one edge of the top and a button 21 which secures the opposite edge. 60

In the construction herein shown the hover chamber has an exit and ventilation opening 3 at one side, this extending from the floor upward, and, as here shown, entirely across one side. It is evident that the 65 length of this opening may be increased or diminished, and extended about more than one side if desired. In fact it may be provided on all sides. It is preferred that the effective height of this opening be varied, 70 by using a movable member therein. In Figs. 1 and 2, this consists of a plate 4 sliding in guide ways 40 and controlled by a threaded rod 41 which passes through lugs 42 carried by the brooder body and the 75 slide. In Fig. 3 the same result is secured by hinging a board 5 and adjusting its height by a cord 50. The means employed for controlling this opening is immaterial.

As a means of heating, a lamp 6 is shown, 80 the chimney 60 fitting into an extension 61 which passes through the top of the brooder. Surrounding the chimney is a cylindrical drum 7 through which and outside the chimney 60, the air passes and is thereby 85 heated. As a substitute, an electric lamp or resistance coil, hot water, or any other heating agent may be employed.

To prevent or substantially reduce the radiation of heat from this drum into the 90 hover chamber, the drum is given a lining 70 of asbestos or other suitable nonconductor.

While the lamp and surrounding drum 7 is shown as within the hover chamber, they may be placed at any point desired even 95 without the chamber. Also any other means for heating the air may be employed.

Trial of a brooder of this type demonstrates that the chickens are comfortable at any point in the brooder chamber, and that 100 the temperature of the air in the lower layers occupied by the chickens may be varied by raising or lowering the slide 4 or door 5 by which the exit opening is controlled, without any adjustment of the lamp. In 105 fact, the large area of the exit opening 3 acts as an automatic regulator to compensate for any variation in the intensity of heat

supplied. Further, absolutely fresh air is constantly being supplied and the chicks are maintained in healthy condition.

An important result secured is that where-
5 in the ventilation system is such that over-
heating and undercooling is automatically
prevented without requiring exact control of
the heating means, and in any fact without
requiring the movement of any part of the
10 device.

The large area of the exit opening and
this being an essential part of the ventilation
system, provides an automatic safe-
15 guard against overheating and undercool-
ing. Should the heat given off by the heater
be more than is necessary, it will produce
an accelerated circulation of air through the
brooder thereby discharging more heat and
20 distributing the heat units among a greater
volume of air, while with the heat given off
reduced below normal, the circulation is
slowed down, requiring less heat units to

properly heat the air. These results follow
from the excess size of the exit opening and
its location at a low level.

Having thus described our invention, what
we claim as new, and desire to secure by
Letters Patent of the United States of
America, is:—

A brooder having a hover chamber and an 30
adjoining open top exercising compartment,
a passing opening in the bottom part of the
wall between said compartments; a door
controlling said passing opening said door
being movable to raise and lower its lower 35
edge, the exercising compartment having
walls fitting closely the ends of said door,
and means for delivering heated air to the
upper part of the hover compartment.

Signed at Seattle, Washington this 15th 40
day of June 1915.

HUGHBERT W. McCRABBE.
HOMER F. NORTON.
